UNITED STATES PATENT OFFICE.

WILLIAM ELMENTHALER, OF CLEVELAND HEIGHTS, OHIO.

SIFTING DEVICE.

Application filed January 15, 1927. Serial No. 161,307.

My invention relates generally to devices for sifting materials and particularly to shovel-like devices which have sifting means.

One of the objects of my invention is to 5 provide a simple, inexpensive, and efficient sifting device.

Another object of my invention is to provide a simple, inexpensive, and efficient shovel-like sifting device.

10 Another object of my invention is to provide a simple, inexpensive, and efficient shovel-like sifting device which is easily manipulated for either sifting or shoveling purposes.

15 Another object of my invention is a simple, effective, and efficient joint between a screen and the supporting frame thereof.

Another object of my invention is a simple, effective, and efficient binder for unsup- 20 ported edges of screens.

A device embodying the features of my invention is shown on the accompanying drawing in the form of a shovel-like sifting device; my invention, however, is ap- 25 plicable to other forms.

In the accompanying drawing:—

Fig. 1 is a general perspective view of a shovel-like sifting device embodying the features of my invention.

30 Fig. 2 is an end view of the front end of Fig. 1, on a larger scale, showing more clearly the relations of the binder and the frame.

Fig. 3 is a section, on a larger scale, taken on a transverse plane indicated by the line 3—3 in Fig. 1, showing more clearly the 35 relations of the screen and the frame and the structure of the joints between the frame and the screen and the structure of the supporting edges of the screen.

40 Fig. 4 is a sectional view of the front end of Fig. 1, on a larger scale, taken in a longitudinal plane indicated by the line 4 in Fig. 1, showing more clearly the cross-sectional formation of the binder and the relation thereof to the screen and to the frame 45 members.

Fig. 5 is a section, on a larger scale, taken in a transverse plane indicated by the line 5—5 in Fig. 1, showing the relation between 50 the frame members and the handle and the fastening or clamping means thereof.

Fig. 6 is a sectional view, on a larger scale, taken in a longitudinal plane indicated by the line 6 in Fig. 1, showing the 55 relations between the base bar and the binder and the frame and the screen.

Similar reference characters refer to similar parts throughout the views.

The device shown in the accompanying drawing comprises, principally, the frame 60 members A and B, the screen C, the binder D, and the handle E.

The frame is made of material having a channel formed cross-section and comprises the component parts A and B, both together 65 forming the complete frame when all of the elements of the device are assembled.

The part A comprises the longitudinal portion 10 and the middle portion 11 bent inwardly and substantially at right angles 70 to the portion 10, and the end portion 12 bent outwardly and substantially at right angles to the portion 11 and inclined upwardly so that the handle E will be disposed at an angle to the screen C when the device 75 is assembled.

The part B comprises the longitudinal portion 13 and the middle portion 14 bent inwardly substantially at right angles to the portion 13, and the end portion 15 bent outwardly and substantially at right angles 80 to the portion 14 and inclined upwardly at the same angle as the end 12 and forms a component part with the end 12 to grip or clamp the handle as will be explained further hereinafter.

The parts A and B are bent so that all of the flanges and all of the hollows of the channel sectioned material thereof face inwardly or toward each other for the purpose 85 appearing presently.

The screen C, of any suitable material or mesh, has three edges thereof bent upwardly and doubled up downwardly over the portion first bent and on the outside thereof to 90 form the support edges 16. This structure provides a simple and efficient support or strengthening means for the screen and aids materially in supporting the screen as well as in effecting a joint between the screen and the frame.

The flanges 16 rest on the inner surface of the lower flanges of the portions 10, 11, 13 and 14 and abut the inside of the webs of the portions just mentioned.

105 This structure of disposing the extreme edges of the screen between the webs of the frame members and other portions of the screen prevents the fraying out of the screen and also provides an unobstructed screening 110 surface.

The fastening means between the screen

and the frame comprise the rivets 17 extending through open portions of the screen and through the webs of the frame with the washers 18 between the head of the rivets and the flanges 16; these elements being firmly riveted against the webs of the frame.

The binder D is formed of sheet metal bent over the front and free end 19 of the screen C and has the ears 20 bent up from the portion 21 and the ears 22 bent up from the portion 23. The end 19 of the screen extends in between the portions 21 and 23 and these portions have the indentations 24 forced down into open portions of the screen to stiffen the binder and to hold the same firmly onto the end 19 of the screen. The front end of the flanges 16 of the screen extends in between the ears 20 and 22 and the ears 22 abut the inside of the web of the portions 10 and 13. The rivets 25 extend through the ears 20 and 22 and through the flanges 16 and through the webs of the portions 10 and 13 and are securely riveted in position.

This structure not only provides a binder for the otherwise free front edge of the screen but also stiffens the screen and helps to support the same and forms an effective tie between the front outer ends of the portions 10 and 13 and provides a smooth end for the screen when the device is used as a shovel.

The handle E has the stem 26 which has the straps 27 secured to the sides of the outer end thereof by means of the rivets 28. The handle member 29 extends between the straps with the longitudinal axis thereof parallel with the plane of the screen C to facilitate the sifting and shoveling operations of the device.

The inner end of the stem 26 extends in between the ends 12 and 15 and is disposed in the hollows thereof. The ends 12 and 15 are clamped against the inner end of the stem 26 by means of the rivets 30.

When the stem 26 is made of wood or other comparatively soft material, the tightening of the rivets forces the portions 31 of the flanges into this soft material and thereby automatically forms the grooves 32 therein. This groove formation aids materially in retaining the stem in proper relation to the front end of the device.

When the stem 26 is made of metal or of material which can not be depressed by the riveting process mentioned, the grooves 32 may be cut into or otherwise formed in the stem 26 so that the portions 31 may engage therein to hold and to maintain the front of the device in proper relation to the handle.

Due to the open front end of the device shown and described, the same can be used similar to a shovel to easily deposit siftable material thereon and to easily remove ma-

terial therefrom. The handle E affords a convenient means for operating the sifter with the operator located away from the sifting end of the device so that dust or the like, as from ashes for instance, do not reach him so easily while he is sifting.

My invention has many advantages some of which are exemplified in the device shown and described. In sifting ashes for instance with the device shown and described, the shovel end of the device can easily be inserted into the ashpit of a furnace and a quantity of the ashes in the ashpit can be deposited thereon in a manner similar to a shovel; the sifting operation is performed while the shovel end is still in the ashpit; this eliminates the handling and the sifting of the ashes outside of the ashpit and consequently eliminates all dust outside of the ashpit; whatever dust is created in the sifting operation is carried away through the exhaust flue of the furnace; all material which remains on the device after sifting (usually material which is not completely burned) can easily be returned to the combustion chamber of the furnace by the device (as a shovel) without creating dust or without extra handling of the material; and nothing more than the final incombustible ashes need to be removed from the ashpit; therefore, the device saves fuel, eliminates dust, and is convenient of operation.

I am aware that my invention can be applied to devices other than the ash sifter device shown and described and that various changes in the structure as well as in the arrangement of elements may be made within the scope of the appended claims; therefore, without limiting myself to the precise structure and arrangement of elements shown and described, nor to the precise application of my invention as shown and described, I claim:

1. A device of the character described having a frame made of channel section material with all of the flanges thereof convergent toward the middle of the device.

2. A device of the character described having a frame made of U-shaped channel section material and having ends thereof spaced apart with the flanges thereof facing each other to form a socket to grip a handle and to confine the same in all lateral directions.

3. A device of the character described including a frame made of U-shaped channel section material with the flanges thereof convergent toward the middle of the device, and a screen supported on said frame in the hollow portion thereof.

4. A device of the character described including a screen supported by edges thereof, and said edges doubled up to increase the supporting capacity thereof.

5. A device of the character described in-

cluding a screen having one edge thereof unsupported, and a sheet metal binder bent over said one edge and over the sides adjacent to said edge and portions thereof indented into open portions of said screen to retain said binder on said screen and to stiffen the same.

6. A device of the character described including a frame having one open end, a screen supported in said frame, a binder over the edge of said screen at said open end of the frame, and a base bar between said binder and the opposite end of said frame and disposed on the bottom of said screen.

7. A device of the character described including a frame composed of two component parts each made of channel section material and having a screen support portion and a handle support portion, the flanges of said two parts facing each other, a screen supported in the hollow of said screen support portions, and a handle clamped between said support portions.

8. A device of the character described including a frame composed of two compo-

nent parts each made of channel section material and having a screen support portion and a handle support portion, the flanges of said two parts facing each other, the front end of said frame being open, a screen supported in the hollow of said channel parts, a binder over the unsupported edge of said screen, and a handle clamped between said handle support portions of said frame.

9. A joint between a channel section member and a screen comprising a double up edge of said screen resting on one of the flanges of said channel member and abutting the web thereof, and a fastening member extending through an open portion of said screen and through said web and having means for engaging some of the material of said screen.

10. A binder for an edge of a screen comprising a sheet bent over the end and over both sides of said edge and portions thereof indented into open portions of said screen to stiffen said binder and to retain the same on said edge of the screen.

WILLIAM ELMENTHALER.
